(57) **CLAIM**

The ornamental design for a fall protection safety rail trolley as shown and described.

DESCRIPTION

FIG. 1 is a perspective view of a fall protection safety rail trolley, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a further perspective view thereof with an environmental structure shown in broken lines.

The broken lines in the drawings illustrate portions of the fall protection safety rail trolley that form no part of the claimed design.

1 Claim, 8 Drawing Sheets
